DESIGN FOR A COMBINED COVER AND CONTAINER FOR BATH SALTS

Robert B. Karoff, New York, N. Y.

Application January 4, 1941, Serial No. 97,810

Term of patent 3½ years

To all whom it may concern:

Be it known that I, Robert B. Karoff, a citizen of the United States of America and a resident of the city, county, and State of New York, have invented a new, original, and ornamental Design for a Combined Cover and Container for Bath Salts, of which the following is a specification, reference being had to the accompanying drawing forming a part thereof.

In the drawing:

The rear is substantially plain.

I claim:

The ornamental design for a combined cover and container for bath salts, substantially as shown and described.

ROBERT B. KAROFF.
